[57] CLAIM

The ornamental design for combined under bed storage and frame unit, as shown and described.

DESCRIPTION

FIG. 1 is a front, left side and top perspective view of combined under bed storage and frame unit showing my new design;

FIG. 2 is a front elevational view thereof;

FIG. 3 is a top plan view thereof;

FIG. 4 is a left end elevational view thereof, the right end elevational view being a mirror image; and,

FIG. 5 is a rear elevational view thereof.

The portions of FIGS. 1, 2, 4 and 5 shown in broken lines represent a bed and frame and form no part of the claimed design, and the bottom of the design is essentially plain and unornamented.
